Patented Sept. 4, 1962

193,524

DISH STORAGE RACK

Victor R. Romero, Albion, Mich., assignor to Union Steel
Products Company, Albion, Mich.

Filed Jan. 15, 1962, Ser. No. 68,303

Term of patent 14 years

(Cl. D44—29)

Fig. 1.

Fig. 4.

Des. 193,524

PAGE 2

FIG. 1.

FIG. 1 is a front perspective view of a dish storage rack, showing my new design; with a cup and a plate shown in broken lines for purposes of illustration.

FIG. 2 is an end perspective view from the right of FIG. 1.

FIG. 3 is an end perspective view from the left of FIG. 1.

FIG. 4 is a rear view.

FIG. 5 is an end elevational view from the right of FIG. 1, the dishes indicated by dotted lines in FIG. 1 being omitted.

I claim:

The ornamental design for a dish storage rack, as shown and described.
